ARTICLE OF FURNITURE

Herman Rueter, Toledo, Ohio, assignor to The
Herrick Manufacturing Company, Toledo,
Ohio, a Corporation of Ohio

Application December 26, 1931
Serial No. 583,363

1 Claim. (Cl. 155—61)

This invention relates to articles of furniture, but particularly to chairs and the like, and an object is to produce a chair having the new and improved features of construction, arrangement 5 and operation hereinafter described.

An embodiment of the invention is shown for purposes of illustration on the accompanying drawing, in which:

Figure 1 is a perspective view of the chair; and 10 Figure 2 is a side elevation of the chair shown in Figure 1 with the fabric covering for the end frame removed and a portion of the end frame broken away.

The illustrated embodiment of the invention 15 comprises a chair having a supporting standard provided with a pair of wooden feet 10 laterally spaced from each other. From each foot rises a pair of upright bars 11 which are spaced from each other, and braces 12 extend across 20 the standard and are secured to each pair of uprights 11. Secured to the upper ends of each pair of uprights 11 is a horizontally disposed cross bar 13 of channel shape.

Disposed between the end frames for swing- 25 ing movement is a seat structure 14, which consists of a wooden rectangular frame 15 containing springs 16 on which is disposed a pad 17. The frame and pad 17 are covered by suitable material, such as canvas 18, thus providing a 30 cushioned seat.

Rigidly secured in pairs to opposite sides of the frame 15 are upright bars 19, a bar being secured to the frame adjacent each corner thereof. The bars 19 terminate at their upper 35 ends above the horizontal bars 13 of the end frames, and secured to each pair of bars 19 is a horizontally disposed arm rest 20, which projects outwardly over the adjacent cross bar 13 and providing substantial cover therefor. Each pair 40 of bars 19 is braced by a diagonal brace 21.

Projecting from the lower end of each rod 19 is an extension 22, which projects below the seat frame 15, and each extension is apertured at 23 to receive U-shaped cradle bars 24. As shown, 45 two bars 24 are provided, one at the front portion of the seat and the other at the rear portion of the seat. The ends of the bars extend upwardly, and are connected by links 25 to the horizontal bars 13 of the end frames. The front 50 bar 24 is connected to the forward end portions of the bars 13, and the rear cradle bar 24 is connected to the rear end portions of the bars 13. This enables the seat to swing forwardly 55 and rearwardly, and militates against sidesway.

A suitably upholstered back 26 is hingedly con-

nected at 27 to the rear of the seat 14. A pair of arms 28 is pivoted to the rear uprights 19 adjacent the upper end thereof, and extend through apertured plates 29 secured to the back 26 and projecting outwardly therefrom. Each 60 arm 28 is provided with a series of notches 30 adapted to engage the plate 29 so that the position of the back may be adjusted as desired. It is to be noted that the same rivets 13 which connect the upper ends of the diagonal braces 21 65 to the uprights 19 also provide pivots for the arms 28.

In order to enhance the appearance of the chair, a canvas covering 32 extends over each end frame. The covering 32 may be in the form 70 of a slip which can be pulled down over each end frame, and the outer side thereof extends to a point adjacent the cross bars 12, whereas the inner side terminates short of the seat 14.

It is to be understood that numerous changes 75 in details of construction, arrangement and operation may be effected without departing from the spirit of the invention, especially as defined in the appended claim.

What I claim as new and desire to secure by 80 Letters Patent is:

A chair comprising a supporting standard having a pair of laterally spaced uprights, a seat structure disposed between said uprights, horizontal braces connecting said uprights and disposed directly beneath said seat structure, said seat structure comprising a seat frame, vertically disposed laterally spaced supporting bars arranged in pairs on opposite sides of said seat frame, means for rigidly securing said vertical 85 bars to said seat frame below the upper ends of said uprights, an extension on each vertical bar projecting below said seat frame, a pair of substantially U-shaped cradle supports for said seat structure, swinging connections between the upper ends of said cradle supports and said laterally spaced uprights, said extensions being apertured to receive said cradle supports whereby the weight of said seat structure is imparted to 90 said cradle supports through said vertical bars, a horizontally disposed arm rest connecting the upper ends of each pair of vertical bars each arm rest projecting laterally over and covering the upper end of the adjacent upright, a back 95 rest, and means connecting said back rest to said 100 seat frame.

HERMAN RUETER.
